UNITED STATES PATENT OFFICE.

BERNARD HOLZ, OF CLEVELAND, OHIO, ASSIGNOR TO THE FRANKELITE CO., OF CLEVELAND, OHIO, A CORPORATION OF OHIO.

DESIGN FOR A SURFACE ORNAMENTATION FOR AN ARTICLE OF MANUFACTURE.

58,328.

Specification for Design.

Patented July 12, 1921.

Application filed May 9, 1921. Serial No. 468,165. Term of patent 7 years.

To all whom it may concern:

Be it known that I, BERNARD HOLZ, a citizen of the United States, and residing at Cleveland, in the county of Cuyahoga and State of Ohio, have invented a new, original, and ornamental Design for Surface Ornamentation for an Article of Manufacture, of which the following is a specification, reference being had to the accompanying drawing, forming part thereof.

My design is adapted to be applied to any article of manufacture wherein the purpose is to ornament the surface of the same, for it is designed as a surface ornamentation, as

distinguished from effecting, or bringing out, pleasing contours. Thus, it is obvious it may be applied to a large variety of articles, such as lighting-fixture parts, jewelry, ornamental pieces of a home, or, in fact, any article which it may serve to ornament.

The figure shown in the drawing is a plan view of my new design.

I claim:

The ornamental design for surface ornamentation for an article of manufacture as shown and described.

BERNARD HOLZ.
